CLAIM

The ornamental design for a pharmaceutical blister package, substantially as shown and described.

DESCRIPTION

FIG. 1 is a top perspective view of a pharmaceutical blister package showing my new design;

FIG. 2 is a top plan view;

FIG. 3 is an end elevational view thereof; and

FIG. 4 is a side elevational view thereof.

The bottom is plain and unornamented but has the slit seen in FIGS. 1 and 2.
